United States Patent Office.

D. A. GILBERT, OF MORRISTOWN, VERMONT.

Letters Patent No. 77,030, dated April 21, 1868.

IMPROVED BUTTER-TUB.

The Schedule referred to in these Letters Patent and making part of the same.

TO ALL WHOM IT MAY CONCERN:

Be it known that I, D. A. GILBERT, of Morristown, in the county of Lamoille, and in the State of Vermont, have invented certain new and useful Improvements in Butter-Tubs; and do hereby declare that the following is a full, clear, and exact description thereof, reference being had to the accompanying drawings, and to the letters of reference marked thereon.

In the annexed drawings, making part of this specification, A represents a pail or tub for holding butter, which may be constructed generally in any of the well-known and usual ways. To the outside of the tub, and extending a little above its upper edge, are three metallic bars, B B B, which are secured at equal distances apart. These bars are formed as represented, having grooves in their inner faces to receive the rim of the cover C. The cover is provided with an annular shoulder, as seen at x, which fits snugly within the mouth of the tub, for the purpose of assisting in holding it in place, and the same time assisting in making it air-tight. The rim of the cover extends over the upper edge of the tub, and is provided with three slots, D D, through which the bars B B pass, to enable the rim to fit snugly down upon the edge of the tub.

When the cover has been fitted upon the tub, by passing the upper ends of the bars B through the slots D, said cover is turned partially around, so that its rim will enter the grooves in the bars for the purpose of holding it securely in position. Packing a, made of felt or rubber, or other suitable material, is secured on the under side of the rim, at that point where the said rim fits upon the edge of the tub. e e represent wedges, which are forced between the upper side of the rim of the cover and the upper lips of the grooves in bars B B, for the purpose of pressing the cover and its packing firmly down upon the edge of the tub, for the purpose of making said tub perfectly air-tight. The grooves in the bars B B are intended to be made a little flaring, or wedge-shaped, so that they will readily receive and retain the wedges e e, as is represented in fig. 3.

By this arrangement I am enabled to make a very simple, cheap, and effective butter-tub—a tub which will exclude the atmosphere, and consequently keep butter fresh and pure.

Having thus fully described my invention, what I claim as new, and desire to secure by Letters Patent, is—

The bars B B, constructed as described, and used in combination with the cover C, packing a, and ridges e e, as and for the purpose set forth.

In testimony that I claim the foregoing, I have hereunto set my hand, this 4th day of April, 1868.

D. A. GILBERT.
